(57) **CLAIM**

The ornamental design for a "handgrip-actuated interface for intelligent lifting device", as shown and described.

DESCRIPTION

FIG. 1 is a perspective view of the top, front and right side of the handgrip-actuated interface for intelligent lifting device;

FIG. 2 is a front elevation view of the handgrip-actuated interface;

FIG. 3 is a right side elevation view of the handgrip-actuated interface;

FIG. 4 is a rear elevation view of the handgrip-actuated interface;

FIG. 5 is a left side elevation view of the handgrip-actuated interface;

FIG. 6 is a top plan view of the handgrip-actuated interface; and,

FIG. 7 is a view looking upwardly at the handgrip-actuated interface from below.

The broken-lines of FIGS. 1 through 7 depict a connector for flexible electrical conduit at the top of the device, a digital readout and fasteners on the cover near the top of the device, and a hook for lifting cargo at the bottom of the device. These broken line features are depicted for illustrative purposes only, and form no part of the claimed design.
